PROCESS FOR THE PRODUCTION OF HIGH-INDENE-CONTENT HYDROCARBON OILS

Karl H. Engel, West Englewood, N. J., assignor, by mesne assignments, to Allied Chemical & Dye Corporation, a corporation of New York

Application May 15, 1940, Serial No. 335,329

9 Claims. (Cl. 202—42)

This invention relates to the production and purification of indene-containing oils, and more particularly to the production of hydrocarbon oils of a high indene content from hydrocarbon oils of relatively low indene content.

Indene has heretofore been recovered from crude indene-containing hydrocarbon oils by treating them with substances such as sodium amide or potassium hydroxide whereby the alkali metal compound combines with the indene to produce a compound which separates from the hydrocarbon oils. The indene is then recovered from the compound thus formed by hydrolysis. Indene has also been recovered from indene-containing hydrocarbon oils by fractionating the oils to obtain a fraction having an indene content of about 80% and then cooling the fraction to temperatures of about —25° C. to cause the indene to freeze and separate from the oils. Fractionation of indene-containing hydrocarbon oils by the usual distillation methods, no matter how carefully conducted, fails to produce oils of an indene content substantially higher than 80-81% for the reason that many of the oils contained in crude indene-containing hydrocarbon oils have practically the same boiling point as indene itself. None of the above methods of obtaining indene have been found to be commercially satisfactory from an economic viewpoint.

It is an object of this invention to provide a simple and inexpensive method of obtaining oils of high indene content from oils of relatively low indene content. Other objects of this invention will appear from the following detailed description.

This application is directed to a species of the generic invention disclosed and claimed in my copending application Serial No. 335,331. The species involves the distillation of hydrocarbon oils of relatively low indene content in the presence of phenol, C_6H_5OH . Phenol, on addition to the hydrocarbon oil of relatively low indene content, forms with the constituents of the oil azeotropes of the minimum-boiling type; i. e., they distill at temperatures lower than the distillation temperatures of any of the azeotrope constituents. Furthermore, I have found that the azeotropes formed with the non-indene oils contained in a fraction from which relatively high-boiling constituents have been previously removed have substantially lower distillation temperatures than the distillation temperatures of indene and of the indene-phenol azeotrope, so that on fractional distillation the non-indene oils are distilled off as azeotropic mixtures with phenol, leaving a hydrocarbon oil of high indene content in the still.

Phenol, I have found, is a particularly effective agent for use in separating indene by the process of this invention. Since the phenol-non-indene azeotropes distill at temperatures

substantially below the distillation temperatures of the phenol-indene azeotrope and of indene itself, separation of the indene and non-indene oils by distillation may be efficiently carried out.

Moreover, phenol tends to inhibit heat polymerization of the indene during distillation of the phenol-indene-containing oil mixture. The phenol is also readily separable from the distillate by extraction.

Indene-containing oils, as is well known, may be obtained by fractional distillation of coal tar oils, drip oils, carburetted water-gas tar oils, oil-gas tar oils, and light oils recovered in coal gas and water-gas operations. In accordance with this invention, the indene-containing hydrocarbon oils are mixed with phenol so as to form azeotropes with indene and the non-indene oils and the mixture is fractionally distilled to effect the separation of the non-indene azeotropes from the indene. Distillation may be carried out under reduced pressures if desired, thus permitting greater heat economy without affecting the efficiency of the separation of indene and non-indene oils. It should be noted the ratio of hydrocarbon oil to phenol in the azeotrope may increase at reduced pressures. Since the azeotropes formed by phenol with the non-indene oils are of the minimum-boiling type, it has been found desirable before the addition of the phenol to subject the indene-containing hydrocarbon oils to be treated according to the invention to ordinary fractional distillation in order to remove non-indene oils of substantially different boiling range from indene, particularly those of substantially higher boiling range than indene. The removal of these oils reduces the amount of phenol required for the distillation, minimizes contamination of the high-indene-content product by azeotropes formed of phenol and higher boiling non-indene oils, and increases the yield of indene by reducing the volume of material which must be distilled, thus lessening the amount of indene carried into the distillate.

The amount of phenol added to the indene-containing hydrocarbon oil should be regulated so that there will not be an undue amount remaining in the still residue when fractional distillation is discontinued. However, there should be enough phenol present so that the azeotropic ratio of phenol to non-indene oils in the distillate will be maintained throughout the fractionation. The entire amount of phenol may be added to the indene-containing hydrocarbon oil before fractionation or the phenol may be added gradually in a continuous or intermittent fashion during the course of the fractionation.

At the beginning of the fractionation the distillate consists almost entirely of the azeotropic mixture of phenol and the non-indene oils, but as fractionation proceeds and the temperature approaches the distillation temperature of the phenol-indene azeotrope, the indene content of

the distillate gradually increases. The course of fractionation may be followed by taking samples of the distillate and testing them for their indene content. The point at which fractionation is discontinued depends upon the indene content of the hydrocarbon oil being treated and also upon the desired indene content of the final product. Thus the lower the indene content of the hydrocarbon oil being treated and the higher the desired indene content of the final product, the longer fractionation must be continued. Obviously, the longer fractionation is continued, the smaller will be the yield of the desired high-indene-content hydrocarbon oil. If desired, fractionation may be continued until substantially the entire indene content of the charge has been distilled, thereby recovering from the last distillate cut a hydrocarbon oil containing about 98% indene. Fractionation of the mixture, however, is ordinarily discontinued when the indene content of the distillate shows the still residue contains about 89% to 92% indene (exclusive of phenol, if any), and the still residue is then distilled straight, i. e. without fractionation, obtaining thereby the desired high-indene-content hydrocarbon oil.

The distillate recovered during the course of the fractionation contains substantially all the phenol and varying amounts of indene, in addition to the non-indene oils removed from the indene-containing hydrocarbon oil. The distillate may be treated in any suitable manner to recover the phenol. Preferably the phenol is extracted from the distillate oil with aqueous alkali in the form of a phenolate, and then recovered from the phenolate solution by blowing with carbon dioxide. The recovered phenol may then be reused. The distillate oil fractions, which contain appreciable quantities of indene, may be refractionated, as described, phenol being added as necessary, to recover the indene contained therein; or the distillate oil may be treated in the ordinary manner with sulfuric acid to polymerize the indene and obtain hydrocarbon oils for solvent purposes and the like.

The accompanying drawing is a flow diagram illustrating a preferred method of carrying out the process of my invention.

Reference numeral 1 indicates an azeotropic fractional distillation operation in which a mixture of phenol and a close-cut indene fraction, e. g. a drip oil high-flash naphtha fraction of boiling range 176°-183° C., enter the process as indicated at 2 and are subjected to azeotropic distillation. As above indicated the overhead product consists primarily of an azeotrope of phenol and non-indene components of the oil. This mixture is washed with an aqueous alkali solution as indicated at 3 to convert phenol to phenolate; the resulting phenolate solution is blown with carbon dioxide as indicated at 4 to separate phenol. Phenol vapor present in the spent carbon dioxide withdrawn at 5 may be recovered by condensation. The low indene oil from which phenol has been removed, withdrawn 63 from the alkali wash operation as indicated at 6, as above stated may contain appreciable quantities of indene; this oil may, therefore, be re-refractionated, with the use of phenol or other azeotropic agent if desired, to recover indene contained therein.

The high indene oil withdrawn as residue from the azeotropic fractionation may contain traces of phenol; phenol present in this oil may be removed by washing with aqueous alkali solution 75

as above indicated. The high indene oil is then subjected to distillation as indicated at 7 to produce an indene distillate which may contain up to about 98% indene. The high boiling residue which contains some indene may be treated to recover the indene contained therein. The indene distillate may be further subjected to a chilling operation, indicated at 8, as hereinafter described and the solid indene thus formed may be separated by filtration as indicated at 9. The filtrate from this operation may be reworked to recover indene contained therein.

The following examples are illustrative of the practice of this invention. Amounts are given in parts by volume. The indene percentages were calculated from the relation of the specific gravity of the oil to that of a similar oil of known indene content.

Example 1.—500 parts of drip oil high-flash naphtha of a boiling range from 176° to 183° C., a specific gravity at 22° C. of 0.957 and an indene content of 78% were mixed with 125 parts of phenol. This mixture was then fractionated in a 32-ball 7-foot column. Distillate cuts of 50 parts each were tested to determine their specific gravity, the phenol was then removed by washing with alkali, the ratio of distillate oil to phenol calculated, and the specific gravity of the phenol-free distillate oil determined. From the specific gravity of the phenol-free oil, its indene content was calculated. The following table shows the results of these tests:

Parts of distillate	Column temp.	Sp. gr. of distillate cut at 22° C.	Ratio distillate oil/phenol	Sp. gr. of distillate oil at 22° C.	Indene distillate oil
0	° C.				Percent
10	150				
30	170				
40	170.5				
50	170.5				
60	171				
80	171.5				
90	171.8				
100	172				
110	172				
130	172.5				
150	172.5	0.948	63/37	0.866	20
160	172.5				
170	173				
200	173	0.952	63/37	0.886	32.5
210	173				
230	173.5				
250	173.5	0.975	62/38	0.915	51
260	173.5				
290	173.5				
300	173.8	0.988	62/38	0.933	62
305	173.8				
310	174.5				
320	175.5				
325	176.5	1.006	62/38	0.965	83
					(No determinations made of these fractions because of small size of fractions)

Fractionation was discontinued after 325 parts of distillate had been recovered and the still residue was then distilled straight, yielding, after removal of the small amount of phenol contained therein, 270 parts of an oil of specific gravity of 0.983 at 22° C. and an indene content of 94%. Thus for every 100 parts of crude high-flash naphtha containing 78% indene, approximately 44 parts of an oil containing 55% indene and 54 parts of an oil containing 94% indene were obtained.

When the same oil was fractionated in the same column at the same rate without the use of phenol, it was impossible to obtain an oil of higher indene content than about 81%.

Example 2.—500 parts of a crude carbolic oil high-flash naphtha cut boiling from 176° to 184° C., having a specific gravity of 0.951 at 22° C. and an indene content of 68% were mixed with 125 parts of phenol, the mixture was fractionated as in Example 1, with the following results:

Parts of distillate	Column temp.	Sp. gr. of distillate cut at 22° C.	Ratio distillate oil/phenol	Sp. gr. of distillate oil at 22° C.	Indene distillate oil	Percent

Fractionation was discontinued after 400 parts of distillate had been recovered. The still residue was then distilled straight, yielding, after removal of the small amount of phenol contained therein, 220 parts of an oil of specific gravity at 22° C. of 0.980, and having an indene content of 91%.

Example 3.—500 parts of crude carbolic oil high-flash naphtha, boiling from 181° to 183° C., having a specific gravity of 0.958 at 22° C. and an indene content of 74% were mixed with 150 parts of phenol and the mixture was fractionated in a packed column at a pressure of about 280 mm. of mercury. Distillate cuts were tested by washing the cuts with alkali to remove the phenol, calculating the ratio of distillate oil to phenol, and then determining the specific gravity of the distillate oil. From the specific gravity of the phenol-free oil, its indene content was calculated. The following table shows the results of these tests:

Parts of distillate	Column temp.	Ratio distillate oil/phenol	Sp. gr. of distillate oil at 22° C.	Indene in distillate oil	Percent
0.....	° C.				
10.....	138				
20.....	138.5				
30.....	138.5				
65.....	139	69/31	0.886	17	
75.....	140				
130.....	140	75/25	0.917	40	
140.....	140				
150.....	141				
195.....	141	75/25	0.956	72	
200.....	141				
210.....	141.5				
255.....	141.5	75/25	0.970	82	

Fractionation was discontinued after 255 parts of distillate had been recovered and the still residue was then distilled straight, yielding, after removal of the remaining phenol contained therein, 305 parts of an oil of specific gravity of 0.983 at 22° C., and an indene content of 92%. Thus for every 100 parts of crude high-flash naphtha containing 74% indene, approximately 37 parts of an oil containing 52% indene and about 61 parts of an oil containing 92% indene were obtained.

If it is desired to obtain pure indene from the hydrocarbon oils of high indene content produced according to this invention, the oils may be cooled to between about -10° and about -20° C. and the solid indene thus formed separated from the oils.

From the above description it will be evident this invention provides a simple and inexpensive method of obtaining hydrocarbon oils of high indene content from hydrocarbon oils of relatively low indene content.

Since certain changes may be made in carrying out the above process without departing from the scope of the invention, it is intended that all matter contained in the above description shall be interpreted as illustrative and not in a limiting sense. Thus, while the above description refers to the addition of phenol to hydrocarbon oils of relatively low indene content, it will be understood that the invention comprehends the production of hydrocarbon oils of high indene content from hydrocarbon oils containing indene and phenol inherently present in amount sufficient to form with the constituents of the oil azeotropes of the minimum-boiling type.

I claim:

1. In a method of producing a hydrocarbon oil of high indene content from a hydrocarbon oil of relatively low indene content, the step which comprises distilling the hydrocarbon oil of relatively low indene content in the presence of an amount of phenol sufficient to form an azeotrope with non-indene components of the oil.

2. In a method of producing a hydrocarbon oil of high indene content from a hydrocarbon oil of relatively low indene content having a boiling range in the neighborhood of indene boiling point, the steps of fractionally distilling the hydrocarbon oil of relatively low indene content in the presence of an amount of phenol sufficient to form an azeotrope with non-indene components of the oil, and recovering the hydrocarbon oil of high indene content.

3. In a method of producing a hydrocarbon oil of high indene content from a hydrocarbon oil of relatively low indene content, the steps of adding an amount of phenol sufficient to form an azeotrope with non-indene components of the oil to the hydrocarbon oil of relatively low indene content obtained by the fractional distillation of coal tar oils, drip oils, carburetted water-gas tar oils, oil-gas-tar oils, and light oils recovered in coal gas and water-gas operations, fractionally distilling the mixture, and recovering the hydrocarbon oil of high indene content from the still residue.

4. In a method of producing a hydrocarbon oil of high indene content from a hydrocarbon oil of relatively low indene content, the steps of adding an amount of phenol sufficient to form an azeotrope with non-indene components of the oil to crude drip oil high-flash naphtha, fractionally distilling the mixture and recovering the

hydrocarbon oil of high indene content from the still residue.

5. In a method of producing a hydrocarbon oil of high indene content from a hydrocarbon oil of relatively low indene content, the steps of adding an amount of phenol sufficient to form an azeotrope with non-indene components of the oil to crude carbolic oil high-flash naphtha, fractionally distilling the mixture, and recovering the hydrocarbon oil of high indene content from the still residue.

6. A method of producing pure indene, which comprises fractionally distilling a hydrocarbon oil of relatively low indene content in the presence of an amount of phenol sufficient to form an azeotrope with non-indene components of the oil, recovering a hydrocarbon oil of high indene content, and cooling the hydrocarbon oil of high indene content to cause pure indene to solidify.

7. A method of producing pure indene from a hydrocarbon oil of relatively low indene content having a boiling range in the neighborhood of indene boiling point, which comprises adding an amount of phenol sufficient to form an azeotrope with non-indene components of the oil to the hydrocarbon oil of relatively low indene content, fractionally distilling the mixture, recovering the hydrocarbon oil of high indene content from the still residue, cooling the recovered oil to between about -10° and about -20° C., and separating pure indene from the cooled oil.

8. In a method of producing a hydrocarbon oil of high indene content, the steps which comprise

fractionally distilling a crude selected from the group coal-tar oils, drip oils, carburetted water-gas tar oils, oil-gas tar oils and light oils recovered in coal-gas and water-gas operations to produce a hydrocarbon mixture of relatively low indene content having a boiling range in the neighborhood of indene boiling point, adding to the resulting hydrocarbon mixture an amount of phenol sufficient to form azeotropes with non-indene components of the oil, fractionally distilling the mixture, recovering phenol from the distillate, recovering the hydrocarbon oil of high indene content from the still residue, cooling the recovered oil to between about -10° and about -20° C., and separating solid indene from the crude oil.

9. In a method of producing a hydrocarbon oil of high indene content, the steps which comprise fractionally distilling a crude selected from the group coal-tar oils, drip oils, carburetted water-gas tar oils, oil-gas tar oils and light oils recovered in coal-gas and water-gas operations to produce a hydrocarbon mixture of relatively low indene content having a boiling range in the neighborhood of indene boiling point, adding to the resulting mixture an amount of phenol sufficient to form azeotropes with non-indene components of the oil, fractionally distilling the mixture at a pressure less than atmospheric, and recovering the hydrocarbon oil of high indene content from the still residue.

KARL H. ENGEL.
